UNITED STATES PATENT OFFICE.

CLINTON L. BOPP, OF HAWKEYE, IOWA.

AUTOMATIC RAILWAY SIGNALING DEVICE.

1,114,429.

Specification of Letters Patent.

Patented Oct. 20, 1914.

Application filed August 10, 1910. Serial No. 576,458.

To all whom it may concern:

Be it known that I, CLINTON L. BOPP, a citizen of the United States, residing at Hawkeye, in the county of Fayette and State 5 of Iowa, have invented certain new and useful Improvements in Automatic Railway Signaling Devices; and I do hereby declare the following to be a full, clear, and exact description of the invention, such as will 10 enable others skilled in the art to which it appertains to make and use the same.

This invention relates to improvements in automatic railway signaling devices, and particularly to the indicator at the station.

15 The object in view is the arrangement in an automatic signaling device, of an indicator provided with a traveling belt having names thereon, and electrically controlled means for moving said belt step by step for 20 bringing into view successively the names on the belt.

To this end the invention comprises certain novel constructions, combinations, and arrangement of parts as will be hereinafter 25 more fully described and claimed, and as is shown in the accompanying sheet of drawings which is a perspective view of the device complete, omitting the inclosing casing.

In forming the indicator embodying the 30 invention, and associating the same with switches and relays, together with a track circuit for operating the same, the various devices are arranged so that the indicating device is set up at the station or at any other 35 desired point, and the switching devices at various points along the track, so as to be operated by means projecting from moving trains passing over the track, whereby the circuit of the indicating device at the station 40 or other point is closed for moving the indicating device and thus causing an indication at all times of the position of the various trains as the same pass over the system.

45 The indicating devices are intended to be placed in stations, hotels, and the like, and wired to be all actuated simultaneously from the same circuit.

The indicating device, more clearly shown 50 in the drawings may be mounted in a suitable housing (not shown) which is made of any desired material for inclosing the operating parts of the machine, and for giving a finished appearance. In a framework 3

55 which may be of any desired material, as for instance metal, to which the various devices

are connected for support, is journaled a pair of axles or supporting shafts 4 and 5, upon which are mounted the drums 6 and 7 which carry an endless web or belt 8. Said 60 web 8 is provided with a plurality of pairs of eyelets 9 for engaging pins 10 and 11 projecting from drums 6 and 7. The web 8 is also provided with the names of the respective stations along the track to which the 65 system is connected, so that as web 8 is fed forward the names of the stations may be brought successively to view through an opening in the front of the housing. Drums 6 and 7 are rigidly secured to shafts 4 and 5 70 which rotate in their bearings, and which also have rigidly secured thereto sprockets 13 and 14. Sprockets 13 and 14 accommodate a chain 15 which passes over a comparatively large sprocket 16. Sprocket 16 75 is rigidly secured to a counter shaft 17 mounted in a pair of cross braces of the frame. A ratchet wheel 18 is rigidly secured to shaft 17 and is rotated in one direction by the reciprocation of an upright actuating 80 pawl 19, and is positively prevented from rotating in the opposite direction by a retaining pawl 20 held against ratchet wheel 18 by spring 21, which spring may be adjusted by a suitable tension screw. Pawl 19 is also 85 held to its work by a spring 22 which may have the tension thereof regulated by an adjusting screw mounted in the upright arm of an L-shaped carrier 23 which is pivotally mounted at 24 upon frame 3, and whose 90 horizontal arm supports an armature 25. Said arm has an extension 26 which is permitted any desired play between adjustable stops 27 and 28. A spring 29 is connected with an oblique brace 30 on carrier 23 for 95 holding the carrier 23 in position, and the extension 26 against said stop 28. Pawl 19 is pivoted at 31 to carrier 23 so that whenever magnets 32 are energized and armature 25 is attracted, pawl 19 will be pulled longitudi-

100 nally for rotating one step ratchet wheel 18, and consequently for moving chain 15 so as to cause the ultimate movement of belt 8 a sufficient distance for disclosing to view another name through an opening in the 105 housing. The throw or movement of pawl 19 may be regulated by stops 27 and 28 so as to move ratchet wheel 18 only one notch forward at each movement of the pawl.

In order to hold the web 8 on its supporting and propelling drums, tension rollers 33 and 34 are provided, each of said tension

rollers being formed with grooves 234 for accommodating the pins 10 and 11. These tension rollers 33 and 34 have their shafts 35 and 36 projecting through slots 37 and 38 for permitting an adjustment of the rollers. This adjustment is automatic, the same being made by pivotally mounted fingers 39 and 40 pressing against the shafts 35 and 36 under the tension of springs 41 and 42, 10 which springs may be of the retractile kind or of the compression kind.

In order to permit a free rotation of the drums 6 and 7, but prevent any backward motion thereof, a pawl 43 is provided which 15 fits into notches 44 in a wheel 45. The teeth between said notches are rounded so as to permit the end of pawl 43 to slip freely over the same when the wheel 45 is positively rotated. Wheel 45 is rigidly secured 20 to axle 5 so that any movement of the axle will be communicated to the wheel. Pawl 43 is held against wheel 45 by a suitable tension spring 46 which permits the pawl to slip from one notch 44 to the next as the 25 belt 8 is moved.

Arranged at any desired point, preferably above web 8 and associated parts, are a pair of magnets 47 which when energized will move armature 48, and also a ball or 30 clapper 49 which is connected therewith. At each energization of magnets 47 bell 50 will be sounded at once for indicating that belt 8 has been moved one step forward, the magnets 47 being energized at the same time 35 that magnets 32 are energized. The magnets 47 and 32 are energized from a local circuit connected to binding posts 51 and 52, while the line wires forming the circuit along the track are connected to binding posts 53 and 40 54. Binding posts 53 and 54 are connected with magnets 55 which are energized whenever the track circuit is closed, and when energized attract armature 56 which moves 45 from its back stop 57 to a front stop 58, and connects wire 59 with framework 3, so that the current may pass from stop 58 to binding post 51 which is grounded on the framework 3.

In operation, when a train has passed any 50 station along the track a switch interposed in the circuit will be closed for permitting current to pass through the track circuit, which current will pass through magnets 55 and energize the same. This will cause 55 the closing of the local circuit connected with binding posts 51 and 52. Starting with binding post 52 current flows through wire 60, magnets 32, wire 61, magnets 47, wire 59, stop 58, armature 56, to the framework 3, and from the framework 3 through 60 binding post 51. When current flows in this circuit the web 8 will be moved one step forward and bell 50 will be sounded once, so

that the visual signal will be changed, and also an audible signal given.

The signaling device may be located in as many rooms as desired, at the station or at any other desired place, so that the movement of trains may be observed easily and as desired.

Associated with the indicating device, and assisting in causing the operation thereof, is a track circuit which is connected with binding posts 53 and 54. This track circuit extends for the full length of the track 75 and has interposed therein a plurality of switches, contacts, or circuit closers capable of being actuated by a shoe on the locomotive or motor car passing over the same; but the details of this track circuit, its 80 switches, and the means on the train for closing the latter form no part of the present invention.

What is claimed is:—

1. In an indicator, the combination with 85 a plurality of drums, an endless web moving over said drums, a counter shaft connected with the drums, a ratchet fast on said shaft, and a retaining pawl engaging said ratchet; of an L-shaped carrier having 90 a horizontal arm pivoted in a support and carrying an armature and an upright arm standing under said ratchet, an upright actuating pawl pivoted at its lower end to said horizontal arm and with its upper end 95 engaging said ratchet, a spring connecting this pawl with the upright arm of the carrier, and an electro-magnet below said armature.

2. In an indicator, the combination with 100 a plurality of drums, an endless web moving over said drums, a counter shaft connected with the drums, a ratchet fast on said shaft, and a retaining pawl engaging said ratchet; of an L-shaped carrier having a 105 horizontal arm pivoted in a support and carrying an armature and an upright arm standing under said ratchet, an upright actuating pawl pivoted at its lower end to said horizontal arm and with its upper end 110 engaging said ratchet, a spring connecting this pawl with the upright arm of the carrier, said horizontal arm being projected beyond its pivot, adjustable stops above and below its projected portion, an electro-magnet 115 below said armature, an oblique brace connecting the arms of said carrier, and a spring leading from said brace to a fixed point for raising the armature from said magnet.

In testimony whereof I affix my signature in presence of two witnesses.

CLINTON L. BOPP.
